UNITED STATES PATENT OFFICE.

PATRICK H. MADDEN AND HENRY E. SIMPSON, OF SPARTA, WISCONSIN.

RAILWAY CROSS-TIE, SWITCH-TIE, AND HEAD-BLOCK.

No. 829,278.

Specification of Letters Patent.

Patented Aug. 21, 1906.

Application filed June 14, 1906. Serial No. 321,680.

To all whom it may concern:

Be it known that we, PATRICK H. MADDEN and HENRY E. SIMPSON, citizens of the United States, residing at Sparta, in the county of Monroe and State of Wisconsin, have invented certain new and useful Improvements in Railway Cross-Ties, Switch-Ties, and Head-Blocks; and we do declare the following to be a full, clear, and exact description of the invention, such as will enable others skilled in the art to which it appertains to make and use the same.

This invention relates to improvements in railway cross-ties, switch-ties, head-blocks, and the like; and it consists in the novel construction, combination, and arrangement of parts hereinafter described and claimed.

The object of the invention is to provide a simple, inexpensive, strong, and durable cross-tie composed of cement or other plastic material.

The above and other objects, which will appear as the nature of the invention is better understood, are accomplished by the construction illustrated in the accompanying drawings, in which—

Figure 1 is a perspective view of the improved railway cross-tie, showing the track-rails secured thereto. Fig. 2 is a vertical longitudinal sectional view through the same. Fig. 3 is a vertical transverse sectional view, and Fig. 4 is a detail horizontal sectional view.

Referring to the drawings by numeral, 1 denotes the improved railway cross-tie, which is molded from cement or any other suitable plastic material into rectangular form. In order to strengthen this rectangular body 1, longitudinal strips or bars 2 and transverse 40 connecting strips or bars 3 of corrugated metal are molded within the same adjacent to its bottom, and in order to permit the track-rails R to be secured upon the ties by spikes S wooden blocks 4 are molded in the body 1 at suitable distances from its ends. As shown, these blocks 4 are rectangular in form and extend vertically through the tie-body, their width being considerably less than the width of the body 1, so that the latter is not weakened to too great an extent. Surrounding the tie-body at points where the blocks 4 are located are bands or sleeves 5, of steel or other metal. These are provided for the purpose of strengthening and reinforcing the tie, and in their tops are formed aper-

tures 6, through which the spikes S may be driven. The reinforcing-bands 5 correspond in shape to the cross-section of the tie-body, which, it will be understood, may be rectangular, as shown, or of any other shape. 60

The construction, use, and advantages of this invention will be readily understood from the foregoing description, taken in connection with the accompanying drawings. It will be seen that this tie will be stronger 65 and much more durable than the wooden tie and that it may be produced at a comparatively small cost. The provision of the wooden blocks in the same permits the rails to be spiked upon it in the usual manner, and 70 the provision of the metal reinforcing-bands compensates for the weakening of the tie caused by molding the blocks in it. The metal bands also serve to protect the wooden blocks from the elements and prevent them 75 from brooming or crushing out of shape. These bands are adapted to be removed when it is necessary to replace new blocks for old ones that have become rotten.

While we have shown and described the invention as embodied in a railway-tie, it will be understood that it may be embodied in switch-ties, head-blocks, and similar devices.

Various changes in the form, proportion, and the minor details of construction may be 85 resorted to without departing from the principle or sacrificing any of the advantages of the invention as defined by the appended claims.

Having thus described our invention, what 90 we claim as new, and desire to secure by Letters Patent, is—

1. A railway-tie or the like comprising a plastic body, a block of wood embedded therein, and a metallic strengthening-band 95 surrounding said tie and said block.

2. A railway-tie or the like comprising a plastic body, a block of wood embedded therein, and a metallic strengthening-band surrounding said tie and said block and having in its top apertures to receive spikes for fastening a track-rail upon said band. 100

3. A railroad-tie or the like comprising a body of plastic material, blocks of wood molded therein, and metal reinforcing-bands 105 covering said blocks and surrounding said tie and having apertures in their tops, substantially as described.

4. A railway-tie or the like comprising a body of plastic material, reinforcing bars or 110

strips molded therein adjacent to its bottom, vertically-extending wooden blocks molded in said tie adjacent to its ends, and metal reinforcing-bands covering said blocks and surrounding said tie and formed in their tops with apertures, substantially as shown and described.

In testimony whereof we have hereunto

set our hands in presence of two subscribing witnesses.

PATRICK H. MADDEN.
HENRY E. SIMPSON.
